RAILWAY TRAFFIC CONTROLLING APPARATUS

Filed May 25, 1923

UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 25, 1923. Serial No. 641,388.

My invention relates to railway traffic controlling apparatus, and particularly to apparatus of the type wherein train carried governing mechanism is controlled by energy received from the trackway.

In one arrangement of apparatus of the type mentioned, it has been suggested to employ the usual track circuit current, that is, the current which energizes the track relays for controlling the train carried governing mechanism, such control being effected by this current through the medium of receiving appliances at the front end of the train. When this is done, it is obvious that the source of track circuit current must always be connected across the rails ahead of a train.

In the case of a double track railroad wherein traffic on each track normally moves in one direction only, this requirement is readily met in so far as train movements in the normal direction are concerned, because the source of track circuit current for each section of track is then connected across the rails adjacent the exit end of each section in accordance with standard practice in automatic block signaling. In the case of single track roads, however, it is necessary for trains to proceed over the track in both directions, and in such instances with only the trackway apparatus thus mentioned, trains moving in one direction would not receive track circuit current. One feature of my invention is the provision of means located in the trackway for connecting a source of track circuit current across the rails at either end of each section, thus permitting train movements in both directions over a single track.

I will describe one form of trackway apparatus embodying my invention, and will then point out the novel features thereof in claims.

The accompanying drawing is a diagrammatic view showing one form and arrangement of railway traffic controlling apparatus embodying my invention.

Referring to the drawing, the reference characters 2 and 2^a designate the track rails of a railroad over which traffic moves in both directions. These rails are divided by means of insulated joints 1 into a plurality of track sections A—B, B—C, C—D, etc.

Each track section is provided with a track transformer designated by the reference character T with an exponent corresponding to the location, the secondary winding 3 of which is connected across the rails adjacent the left hand end of the section. Interposed between the left hand terminal of this secondary winding 3 and the rail 2^a is an impedance 5, one function of which is to limit the output of transformer T when the associated section is occupied by a train. Another similar transformer, designated by the reference character U with an exponent corresponding to the location, is provided for each section, and the secondary winding 7 of each such transformer is connected across the rails adjacent the right hand end of the associated section. An impedance 6 similar to impedance 5 is interposed between the right hand terminal of winding 7 and rail 2. Two track relays designated by the reference characters R and S with exponents corresponding to the location are provided at the left hand and right hand end of each section. Each section is further provided with a line relay designated by the reference character H with an exponent corresponding to the location, and also with a stick relay and a repeater relay designated by the reference characters E and G, respectively, with exponents corresponding to the locations.

Referring particularly to section B—C, the relay R^b is connected across the rails adjacent the left hand end of the section. Since this relay is thus connected directly across the secondary terminals of transformer T^b, an impedance 9 is inserted in the relay circuit whereby relay R^b is protected from excessive voltage. The relay S^c is provided with a circuit which passes from the rail 2^a, through wire 41, relay S^c, wire 40, back contact 37—39 of repeater relay G^c, and wire 70 to rail 2. This circuit is closed only when relay G^c is de-energized, and at such time it is clear that the section is provided with a track circuit which includes secondary winding 3 of transformer T^b, impedance 5, rails 2 and 2^a and the winding of relay S^c. At the same time relay R^b is energized directly from transformer T^b. The primary winding 4 of transformer T^b is provided with a circuit which

passes from the left hand terminal of the secondary winding 13 of a line transformer F^B , through wires 67, 66 and 65, winding 4, wires 55 and 57, back contact 31—35 of stick relay E^B , and wire 44 back to the right hand terminal of secondary 13 of transformer F^B . This circuit is closed only when relay E^B is de-energized. A branch is provided for this circuit which passes from wire 55, 10 through wire 56, front contact 23—28 of relay H^B , and wire 51 back to wire 44. The circuit through this branch is closed only when relay H^B is energized. The primary winding 12 of transformer F^B is constantly 15 connected to two line wires 79 fed by an alternating current generator 80. It follows that section B—C is provided with track circuit current by transformer T^B when relay H^B is energized, or relay E^B is de-energized. Relay H^B is provided with a circuit which passes from the left hand terminal of secondary winding 11 of line transformer J^C , through wires 43, 67, 66, and 64, relay H^B , wire 63, front contact 18—20 of relay 20 R^B , wire 42, front contact 47—48 of relay S^C , and wires 69 and 68, back to the right hand terminal of secondary 11 of transformer J^C . It follows, then, that relay H^B is energized only when relays R^B and S^C are 25 both energized. The primary winding 10 of this transformer J^C is constantly connected to the line wires 79. Stick relay E^B is provided with a "pick-up" circuit which passes from the left hand terminal of secondary winding 13 of transformer F^B , through wires 67 and 62, relay E^B , wires 77 and 60, front contact 24—27 of relay H^B , wire 75, back contact 46—50 of relay S^B , and wire 45, back to the right hand terminal of 30 secondary winding 13 of transformer F^B . This circuit is closed only when relay H^B is energized and relay S^B is de-energized. A "stick" circuit is provided also for relay E^B passing from the left hand terminal of secondary winding 13 of transformer F^B , through wires 67 and 62, relay E^B , wires 77 and 61, front contact 29—32, wire 53, back contact 19—22 of relay R^B , and wires 52, 51 and 44, back to the right hand terminal of secondary winding 13 of transformer F^B . This circuit is closed only when relay E^B is energized and relay R^B is de-energized. An auxiliary circuit is provided for relay R^B which passes from rail 35 2, through wire 14, relay R^B , wires 15 and 17, back contact 25—26 of relay H^B , wire 59, front contact 30—33 of relay E^B and wire 58 back to rail 2^a. It is clear therefore, that although the relay R^B is constantly connected across the rails of the section in series with an impedance 9, when relay H^B is de-energized and relay E^B is energized the impedance 9 is shunted by the circuit through contact 25—26 of relay H^B and contact 60 30—33 of relay E^B and relay R^B is then

connected directly to the rails. The primary 8 of the track transformer U^C is provided with a circuit which passes from the left hand terminal of secondary winding 11 of transformer J^C , through wires 73 and 71, winding 8, wire 76, front contact 36—38 of relay G^C , and wires 81 and 68 back to the right hand terminal of secondary winding 11 of transformer J^C . It is therefore evident that the section B—C is supplied with 75 track circuit current from transformer U^C only when relay G^C is energized. Relay G^C is provided with a circuit which passes from the left hand terminal of secondary winding 13 of transformer F^B , through wires 43, 73 80 and 72, relay G^C , wire 74, back contact 47—49 of relay S^C , wire 42, back contact 18—21 of relay R^B , wire 54, front contact 31—34 of relay E^B , and wire 44, back to the right hand terminal of secondary winding 85 13 of transformer F^B . This circuit is closed only when relay E^B is energized and relays R^B and S^C are both de-energized.

The operation of the complete apparatus is as follows: As shown in the drawing, all 90 the apparatus is in the normal condition, that is, none of the track sections illustrated in the figure are occupied. Under this condition the two track relays R and S for each section are energized, line relay H for each 95 section is also energized, while the stick relay E and its associated repeater G are de-energized in each section. As a result, transformer T is energized, transformer U is de-energized, and the shunt circuit around impedance 9 is open. I will now assume that a 100 train, proceeding from left to right, enters section A—B. This will de-energize both track relays R^A and S^A . The de-energization of the track relay S^A closes the circuit 105 for the stick relay E^A through the contact 46—50, so that relay E^A becomes energized. This causes no change, however, in the apparatus for section B—C because transformer T^B remains energized through contact 23—28 110 of relay H^B . As the train enters section B—C, it shunts track relays R^B and S^C , thereby causing both of these relays to become de-energized. The de-energization of relay R^B closes the stick circuit for stick 115 relay E^B , so that this relay remains energized as long as the train occupies section B—C. The de-energization of relays R^B and S^C opens the circuit for line relay H^B , so that this relay becomes de-energized. Relay H^B being de-energized, and relay E^B being energized, the low resistance shunt around impedance 9 is closed and remains 120 closed until the train leaves the section. Repeater relay G^C becomes energized because track relays R^B and S^C are both de-energized, and stick relay E^B is energized. The repeater relay G^C , therefore, functions to disconnect track relay S^C from the track rails 125 and to connect the primary 8 of transformer 130

U^c with the secondary of transformer J^c , thereby supplying track circuit current to the rails at the right hand end of section B—C. It will be seen, therefore, that as soon as the train enters section B—C, a source of track circuit current is connected across the rails at the right hand end of the section. As the rear end of the train leaves section B—C, track relay R^b will be come energized by track circuit current from transformer U^c , and the energization of track relay R^b will open stick relay E^b , so that the primary of transformer T^b is again supplied with current. The energization of track relay R^b will also de-energize repeater relay G^c , and the de-energization of the latter relay serves to disconnect the primary of transformer U^c from its source of current and to connect track relay S^c across the rails. This track relay will immediately become energized, due to track circuit current from transformer T^b . Both track relays R^b and S^c thus being energized, relay H^b again becomes energized and the parts of the apparatus associated with section B—C are then restored to their normal conditions.

When a train moving from right to left enters track section B—C, it de-energizes both track relays R^b and S^c . Line relay H^b is, of course, de-energized due to the opening of the track relays. Stick relay E^b cannot now be energized because its circuit is open at contact 24—27 of relay H^b so that transformer T^b continues to supply track circuit current to the rails. Repeater relay G^c remains de-energized, so that track relay S^c remains connected across the rails and the circuit for the primary of transformer U^c remains open. As the train passes out of section B—C, track relays R^b and S^c become energized, and line relay H^b becomes energized, whereupon the parts of the apparatus associated with this source are restored to their normal condition.

It will be seen, therefore, that a train moving in either direction is constantly supplied with track circuit current from a source located at the end of the section toward which the train is proceeding.

Referring now to a train moving from left to right, it will be noted that stick relay E^b becomes energized while the train is in section A—B, but that the track circuit apparatus for section B—C is not reversed until line relay H^b is de-energized by the train actually entering section B—C.

By virtue of my invention I am enabled to provide for reversal of track circuits without trackway signals and without the provision of slow-acting repeating means for the line relay H .

Although I have herein shown and described only one form and arrangement of railway traffic controlling apparatus em-

bodying my invention, it is understood that various changes and modifications may be made therein, within the scope of the appended claims without departing from the spirit and scope of my invention.

70

Having thus described my invention, what I claim is:

1. In combination, a right hand and a left hand section of railway track, a track relay for said left hand section, a stick relay for said right hand section, means for energizing said stick relay as soon as said track relay is de-energized by a train in the left hand section moving toward the right hand section, and apparatus controlled in part by said stick relay for supplying train governing current to the rails of said forward section.

2. In combination, a forward and a rear section of railway track, a track relay for said rear section, a source of alternating current normally connected across the rails adjacent the rear end of said forward section, a second source of alternating current located adjacent the forward end of said forward section but normally disconnected therefrom, a stick relay for said forward section, means for energizing said stick relay as soon as said track relay is de-energized by a train in the rear section moving toward the forward section, and means controlled in part by said stick relay for disconnecting said first source from and connecting said second source to the rails of said forward section when the train enters said forward section.

3. In combination, a forward and a rear section of railway track, a track relay for said rear section, a source of alternating current normally connected across the rails adjacent the rear end of said forward section, a second source of alternating current located adjacent the forward end of said forward section but normally disconnected therefrom, a track relay for each end of said forward section, a line relay controlled by said two last mentioned track relays, a stick relay controlled by said first track relay and said line relay, and means controlled by said stick relay for disconnecting said first source from and connecting said second source to the rails of the section.

4. In combination, two adjacent sections A—B and B—C of railway track, two track relays R^b and S^c adjacent the ends of said section B—C, the former constantly connected with the track rails, means at each end of said section B—C for supplying alternating current to the track rails, a stick relay E^b for said section B—C, a track relay S^b for section A—B, a line relay for section B—C controlled by said track relays R^b and S^c , a circuit for said stick relay including a front contact of said line relay and a back contact of said track relay S^b , and means controlled

by said stick relay for connecting the one or the other of said means to the rails of section B—C.

5. In combination, two track sections A—B and B—C, a track relay for section A—B, a relay for section B—C normally energized but de-energized by a train entering the section, an auxiliary relay for section B—C, a pick-up circuit for said auxiliary relay closed only when said track relay is de-energized, means for normally supplying track circuit current to one end of section B—C, and means effective only when said auxiliary relay is energized and said second relay is de-energized to discontinue said supply of current and to supply track circuit current to the opposite end of section B—C.

6. In combination, a left hand track section A—B and a right hand track section B—C, a track relay for section A—B, a relay for section B—C normally energized but de-energized by a train entering the section, a stick relay for section B—C, a pick-up circuit for said stick relay closed only when said track relay is open, a holding circuit for said stick relay controlled by a back contact of said second relay, and apparatus for section B—C controlled by said stick relay and by said second relay for controlling traffic moving from left to right.

7. In combination, two track sections A—B and B—C, a track relay for section A—B, a relay for section B—C normally energized but de-energized by a train entering the section, a stick relay for section B—C, a pick-up circuit for said stick relay closed only when said track relay is de-energized, means for normally supplying track circuit current to one end of section B—C, and means effective only when said stick relay is energized and said second relay is de-energized to discontinue said supply of current and to supply track circuit current to the opposite end of section B—C, and means for keeping said stick relay closed while a train occupies section B—C.

8. In combination, a right hand and a left hand section of railway track, a track relay for said right hand section, a line relay for said right hand section controlled in part by said track relay, a track relay for said left hand section, a stick relay for said right hand section; a circuit for said stick relay including a source of energy, a front contact on said line relay, and a back contact on said second track relay, and apparatus for said right hand section controlled in part by said stick relay for controlling traffic moving from left to right.

9. In combination, a forward and a rear section of railway track, a track relay for said rear section, a source of alternating current normally connected across the rails adjacent the rear end of said forward section, a second source of alternating current

located adjacent the forward end of said forward section but normally disconnected therefrom, a stick relay for said forward section, means for energizing said stick relay as soon as said track relay is de-energized by a train in the rear section moving toward the forward section, and train controlled means operating when said train enters the forward section to disconnect said first source from and connect said second source with the rails of the section provided said stick relay is energized.

10. In combination, two adjacent sections of railway tracks A—B and B—C, a normally energized relay for section A—B, a source of track circuit current normally connected across the rails of section B—C at the end B, a second source of track circuit current for section B—C located at the end C but normally disconnected from the rails, two track relays R^B and S^C, the first of which is constantly connected across the rails of section B—C at the end B and the latter of which is normally connected across the rails at the end C of section B—C, a line relay H^B controlled by front contacts of track relays R^B and S^C, a stick relay for section B—C provided with a pick-up circuit controlled by the back contact of the relay for section A—B and by a front contact of line relay H^B, a holding circuit for relay E^B controlled by a back contact of track relay R^B, means operating only when relay E^B is energized and relay H^B is de-energized to disconnect from the track rails the source of current located at end B of section B—C, a repeater relay G^C controlled by back contacts of relays R^B and S^C and by a front contact of stick relay E^B, and means operating when the repeater relay G^C is energized to disconnect track relay S^C from the track rails and to connect with the track rails the source of current located at the end C of section B—C.

11. In combination, two adjacent sections A—B and B—C of railway track, two track relays R^B and S^C adjacent the ends of said section B—C, the former constantly connected with the track rails, an impedance interposed between said relay R^B and one of the rails of the associated section, means at each end of said section B—C for supplying alternating current to the track rails, a stick relay E^B for said section B—C, a track relay S^B for section A—B, a line relay for section B—C controlled by said track relays R^B and S^C, a circuit for said stick relay including a front contact of said line relay and a back contact of said track relay S^B, means controlled by said stick relay for connecting the one or the other of said means to the rails of the section B—C, and means controlled by said line relay and said stick relay for at times completing a branch of low resistance around said impedance.

12. In combination, two adjacent sections of railway track A—B and B—C, a normally energized relay for section A—B, two transformers located adjacent the ends of section B—C and having their secondaries constantly connected with the rails of the section, two track relays R^B and S^C, the first of which is constantly connected across the rails of section B—C at the end B, and the latter of which is normally connected across the rails of section B—C at the end C, a line relay H^B controlled by front contacts of track relays R^B and S^C, a stick relay for section B—C provided with a pick-up circuit controlled by the back contact of the relay for section A—B and by a front contact of line relay H^B, a holding circuit for relay E^B controlled by a back contact of track relay R^B, a circuit for the primary of the transformer located at end B of section B—C including a back contact of said stick relay, a branch for said circuit including a front contact of said line relay but not said contact or said stick relay, a repeater relay G^C controlled by back contacts of relays R^B and S^C and by a front contact of stick relay E^B, and means operating when the repeater relay G^C is energized to disconnect track relay S^C from the track rails and to complete the circuit for the primary of the remaining transformer.

13. In combination, two successive sections of track, a stick relay for the second section, means controlled by a train in the first section for energizing said relay if the second section is unoccupied, a track circuit for the second section normally comprising a source of current connected with the rails at the end adjacent the first section, apparatus controlled in part by said relay and in part by train governed apparatus associated with the second section, said first-mentioned apparatus operating to disconnect said source of current from the rails and to connect a second source with the rails adjacent the other end of the second section when a train enters the second section from the first section provided the relay is energized, and means for keeping said relay energized until such train leaves the second section.

14. In combination, a forward and a rear track section, a stick relay for said forward section, traffic controlled means in said rear section for energizing said stick relay when such forward section is unoccupied, and traffic controlled means in said forward section for closing a holding circuit for said stick relay; and means controlled in part by said stick relay and in part by said traffic controlled means in the forward section for connecting train control energy at one end of said forward track section.

15. In combination, a forward and a rear section of railway track, a source of train control energy normally connected with the

rails adjacent one end of said forward section, a stick relay for said forward section, traffic controlled means in said rear section for energizing said stick relay when such forward section is unoccupied and traffic controlled means in said forward section for closing a holding circuit for said stick relay; and means controlled in part by said stick relay and in part by said traffic controlled means in the forward section for disconnecting said first source and connecting a second source of train control energy with the rails adjacent the other end of said forward section.

16. Railway traffic controlling apparatus comprising a section of railway track, a source of track circuit current normally connected across the rails adjacent the left hand end of said section, a track relay connected across the left hand end of said section, a second track relay normally connected across the rails adjacent the right hand end of said section, a line relay controlled in part by said track relays, a stick relay controlled in part by said line relay and arranged to be energized by a train approaching said section before such train enters the section, and means controlled by said stick relay and said first track relay for disconnecting said source of current from the track rails.

17. In combination, a section of railway track, a source of current adjacent one end of the section but normally disconnected from the rails, a normally de-energized relay, means controlled by a train approaching said section from one direction but not from the other direction for energizing said relay before the train enters the section, means for keeping said relay energized while a train which has caused it to become energized is passing through the section, and means controlled by said relay for connecting said source with the rails of said section.

18. In combination, a section of railway track, a first source of current normally connected with the rails adjacent one end of said section, a second source of current adjacent the other end of the section but normally disconnected from the rails, a normally de-energized relay, means controlled by a train approaching said section from one direction but not from the other direction for energizing said relay before the train enters the section, means for keeping said relay energized while a train which has caused it to become energized is passing through the section, and means controlled by said relay for disconnecting said first source from and connecting said second source with the rails of said section.

19. In combination, a section of railway track, a source of current adjacent one end of said section but normally disconnected

from the rails, a normally de-energized relay, means controlled by a train approaching said section from one direction but not from the other direction for energizing said relay before the train enters the section, a track relay for said section, means controlled by said track relay for keeping said normally de-energized relay energized while a train which has caused it to become energized is passing through the section, and means controlled by said two relays for connecting said source with the rails of the section.

20. In combination, a section of railway track, a first source of current normally connected with the rails adjacent one end of said section, a second source of current adjacent the other end of the section but normally disconnected from the rails, a normally de-energized relay, means controlled by a train approaching said section from one direction but not from the other direction for energizing said relay before the train enters the section, a track relay for said section controlled by said track relay, means for keeping said normally de-energized relay energized while a train which has caused it to become energized is passing through the

section, and means operating to disconnect said first source from and connect said second source with the rails of said section when and only when said normally de-energized relay is energized and said line relay is de-energized.

21. In combination, a section of railway track, a first source of current normally connected with the rails adjacent one end of said section, a second source of current adjacent the other end of the section but normally disconnected from the rails, a normally deenergized relay, means controlled by a train approaching said section from one direction but not from the other direction for energizing said relay before the train enters the section, means for keeping said relay energized while a train which has caused it to become energized is passing through the section, and means operating when and only when said relay is energized and a train occupies said section to disconnect said first source from the rails and connect said second source with the rails of the section.

In testimony whereof I affix my signature.

HERBERT A. WALLACE.
